UNITED STATES PATENT OFFICE.

HENRY E. BUTLER, OF SCOTIA, NEW YORK.

LICENSE HOLDER.

Application filed December 1, 1926. Serial No. 152,017.

In certain instances licenses such as are required by hunters and fishermen, for example, comprise a button provided with a pin or other suitable means by which the button is to be attached to the coat or other garment and a license paper which is filled out with certain identification data. The hunter or fisherman is required always to wear the button and to carry the license paper whenever hunting or fishing, and if either is lost, a new license button and paper must be obtained. Often the license paper is lost or the person to whom it is issued fails to have it along with him when hunting or fishing. And in any event, it means two things to carry and to look after whenever going fishing or hunting so as to make sure they are being taken along.

The object of my invention is to provide an improved holder for a button and license paper, and for a consideration of what I believe to be novel and my invention, attention is directed to the following specification and the claims appended thereto.

In the drawing, Fig. 1 is a front perspective view of a holder embodying my invention: Fig. 2 is a perspective view looking from the rear; Fig. 3 is a view similar to Fig. 1 showing the button in place in the holder; Fig. 4 is a view similar to Fig. 2 showing the license paper in the holder; Fig. 5 is a vertical sectional view of the holder, and Fig. 6 is a view of a modification.

Referring to the drawing, the holder comprises a structure having on its front side means for clamping a button and on its rear side means forming a pocket for holding a license paper, the arrangement being such that the usual pin or other fastening means which forms a part of the button is utilized for attaching the holder to a garment of the wearer. In Figs. 1 to 5, the button clamping means comprises a plurality of circumferentially spaced curved spring fingers 7 which project forwardly from a front wall 8 and are adapted to clamp over the edge of the button as is shown clearly in Figs. 3 and 4 wherein 9 indicates a hunting and fishing license button having an attaching pin 10 on its back by means of which it is to be attached to a garment. The upper portion of front wall 8 is provided with an opening 11 from the lower edge of which project two angularly extending fingers 12.

As will be seen from Fig. 4, fingers 12 lie just beneath pin 10 and cooperate with the pin to keep the holder and button from turning relatively to each other.

13 indicates a back wall which cooperates 60 with front wall 8 and two side walls 14 to form a pocket 15 adapted to receive a license paper. The license paper with advantage may be placed in a water proof envelope and inserted into the pocket as is 65 indicated at 16.

In the use of the holder, the license button is placed within the spring fingers 7 as is shown in Figs. 3 and 4 with the pin 10 extending transversely across the holder just 70 above fingers 12. The license paper is placed in the envelope, if one is to be used, and then inserted into pocket 15. The holder is then pinned to a garment of the person carrying the license. When pinned 75 in position, it will be seen that the button serves to maintain the holder securely in position so it cannot become detached. The license paper is held in the pocket at the rear of the holder where it is well protected 80 and where it is not likely to be lost out of the pocket.

By the use of the holder, the hunter, fisherman, or the like is assured of having both his button and his license paper along with 85 him if he has either for they will always be together.

Referring now to the construction of the holder, it will be seen that it is simple in structure so that it is capable of being 90 manufactured at low cost. It lends itself to being manufactured from a single piece of material since the front wall, the back wall, the side walls, and the fingers may be and preferably are formed integral with 95 each other. It may be made readily from sheet material of suitable thickness by a stamping operation. Since the pin on the button serves as the fastening means for the holder, it is not necessary to provide a special fastening means forming a part of the holder. This serves to simplify the manufacture of the holder.

In Fig. 6 I have shown a modification wherein the holding means for receiving the pin is in the form of a threaded shell 17 into which the button screws, there being a ledge 18 at the bottom of the shell which forms a stop for the button. Otherwise the arrangement is the same as that of Figs. 1 to 5. 110

What I claim as new and desire to secure by Letters Patent of the United States, is:—

1. A holder for a license or the like comprising a button having means for attaching it to a garment and a paper, said holder comprising a wall having an opening, means carried by the wall for supporting a button with its attaching means exposed through said opening, and means which forms with said wall a pocket for holding a paper.
- 5 2. A holder for a license or the like comprising a button having means for attaching it to a garment and a paper, said holder comprising a wall having an opening, spring
- 10 15 fingers on the wall for supporting a button

with its attaching means exposed through said opening, and means which forms with said wall a pocket for holding a paper.

3. A holder of the character described, said holder being formed from a single piece 20 of sheet material and comprising a wall having an opening therein, means projecting forwardly from said wall around said opening to form a holding means for a button, and walls integral with said first named wall 25 and providing a pocket at the back of the holder adapted to receive a paper.

In witness whereof, I have hereunto set my hand this 17th day of November, 1926.

HENRY E. BUTLER.
